UNITED STATES PATENT OFFICE.

FRANCIS P. CATLIN, OF HUDSON, WISCONSIN.

IMPROVEMENT IN WINDOW-SASH SUPPORTERS.

Specification forming part of Letters Patent No. 38,372, dated May 5, 1863.

To all whom it may concern:

Be it known that I, FRANCIS P. CATLIN, of Hudson, St. Croix county, State of Wisconsin, have invented certain new and useful Improvements in Window-Sash Supporters; and I do hereby declare that the following is a full, clear, and exact description of the construction and operation of the same, reference being had to the annexed drawings, making a part of this specification, in which—

Figure 1 shows the position of the supporter when holding the sash up; Fig. 2, the position when the sash is going up, and Fig. 3 the position when the sash is going down.

In Fig. 1, K W represent the supporter, which is formed of a single piece of metal having the part K rounded on the end next the sash, and the part W made thicker and heavier, so as to act as a weight or balance to K. A strip of rubber, R, or other elastic substance, is inserted in the sash, as shown in Fig. 1, against which the sash presses. The sash being down, the supporter stands as shown in Fig. 3. Now, when the sash is raised, the part K, being held against the rubber by the weighted part W, is turned so that it is embedded in the rubber R, as in Fig. 1. This presses the sash against the opposite side of the window, and the friction thus produced holds the sash in position. By pushing upward against the sash again the supporter is thrown in the position represented in Fig. 2. The heavy end W then holds the part K

against the rubber ready to be turned when the sash is lowered. The sash can thus be held at any point desired.

This supporter can be placed in a box, a b c d, and can be inserted in the casing at any point where the sash can operate upon it, or may be placed in the sash at any point desired, and the rubber placed in the casing.

Instead of the strip of rubber being placed in the sash or casing, the part K, as shown at B, may be faced with the rubber S, or any other elastic substance, and it can be operated in a similar manner.

I am aware that rubber is already used on periphery of wheels or eccentrics for a similar purpose; but

What I do claim, and desire to secure by Letters Patent, is—

1. The combination of the arm or lever K and the weight W, inserted in the casing as described, with the rubber or other elastic substance R inserted either in the sash or in the lever K.

2. The lever K and weight W, inserted in the sash, with the rubber or other elastic substance attached to either the casing or arm K, substantially as and for the purpose described.

F. P. CATLIN.
